US00D863518S

(12) **United States Design Patent** (10) **Patent No.:** **US D863,518 S**
(45) **Date of Patent:** **** Oct. 15, 2019**

(54) **HEATER**

(71) Applicants: **Mark Fuller**, Sun Valley, CA (US);
Susan Fuller, Sun Valley, CA (US);
James Doyle, Sun Valley, CA (US);
Riae Yoo, Sun Valley, CA (US); **Dezso Molnar**, Sun Valley, CA (US); **Scott Winslow**, Sun Valley, CA (US)

(72) Inventors: **Mark Fuller**, Sun Valley, CA (US);
Susan Fuller, Sun Valley, CA (US);
James Doyle, Sun Valley, CA (US);
Riae Yoo, Sun Valley, CA (US); **Dezso Molnar**, Sun Valley, CA (US); **Scott Winslow**, Sun Valley, CA (US)

(73) Assignee: **WET**, Sun Valley, CA (US)

(**) Term: **15 Years**

(21) Appl. No.: **29/529,851**

(22) Filed: **Jun. 10, 2015**

(51) LOC (12) Cl. **23-03**

(52) U.S. Cl.

USPC **D23/317**

(57) **CLAIM**

The ornamental designs for a heater, as shown and described.

DESCRIPTION

FIG. 1 is a front view of a heater.

FIG. 2 is a left view thereof.

FIG. 3 is a right view thereof.

FIG. 4 is a rear view thereof.

FIG. 5 is a top view thereof; and,

FIG. 6 is a bottom view thereof.

In the drawings, the broken lines depict unclaimed subject matter only and form no part of the claimed design.

1 Claim, 1 Drawing Sheet
